CLAIM

The ornamental design for an electrophoresis wedge-well divider cassette, as shown and described.

DESCRIPTION

FIG. 1 is a front, top and side perspective view of an electrophoresis wedge-well divider cassette, according to our new design;

FIG. 2 is a back, top and side perspective view of the electrophoresis wedge-well divider cassette of FIG. 1;

FIG. 3 is a front view of the electrophoresis wedge-well divider cassette of FIG. 1;

FIG. 4 is a back view of the electrophoresis wedge-well divider cassette of FIG. 1;

FIG. 5 is a right side view of the electrophoresis wedge-well divider cassette of FIG. 1;

FIG. 6 is a left side view of the electrophoresis wedge-well divider cassette of FIG. 1;

FIG. 7 is a top view of the electrophoresis wedge-well divider cassette of FIG. 1; and,

FIG. 8 is a bottom view of the electrophoresis wedge-well divider cassette of FIG. 1.
